CLAIM

The ornamental design for a massage pad, as shown and described.

DESCRIPTION

FIG. 1 is a perspective view of a massage pad showing my new design.

FIG. 2 is a front view of an embodiment thereof.

FIG. 3 is a side view of an embodiment thereof.

FIG. 4 is an end view of an embodiment thereof.

FIG. 5 is a rear view thereof; and,

FIG. 6 is another perspective view of the massage pad shown in FIG. 1 in an environment as part of an inversion therapy table.

The dashed lines shown in the drawing are for illustrative purposes only and form no part of the claimed design. The solid-dash lines represent surface shading.
